CLAIM

The ornamental design for a covered vent, as shown and described.

DESCRIPTION

FIG. 1 is a top perspective view of a covered vent showing my new design;

FIG. 2 is a bottom perspective view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a top perspective view with the cover exploded; and,

FIG. 8 is a cross-section view on line 8—8 in FIG. 3.

The broken line showing of a container seal is for illustrative purposes only and forms no part of the claimed design.
